UNITED STATES PATENT OFFICE.

ESTELLE V. ALLISON, OF NEW YORK, N. Y.

DESIGN FOR A DOLL OR SIMILAR ARTICLE.

Application filed October 19, 1923. Serial No. 7,553. Term of patent 14 years.

To all whom it may concern:

Be it known that I, ESTELLE V. ALLISON, a citizen of the United States, residing at the city of New York, in the county and State of New York, have invented a new, original, and ornamental Design for a Doll or Similar Article, of which the following is a specification, reference being had to the accompanying drawing, forming part thereof.

The figure is a perspective view of a doll embodying my new design. Both the head and the trunk of the doll are substantially spherical, and have spherically shaped depressions therein to simulate golf balls.

I claim:

The ornamental design for a doll, or similar article as shown and described.

ESTELLE V. ALLISON.
